United States Patent Office

Des. 182,949
Patented June 3, 1958

182,949

COMB

Joseph L. Chiariello, Los Angeles, Calif.

Application December 3, 1957, Serial No. 48,755

Term of patent 14 years

(Cl. D86—8)

Fig. 1 is a front elevation view of a comb, showing my new design;

Fig. 2 is a left end elevation view;

Fig. 3 is a right end elevation view;

Fig. 4 is a top plan view;

Fig. 5 is a bottom plan view thereof;

Fig. 6 is a sectional view on line 6—6 of Fig. 1.

I claim:

The ornamental design for a comb, as shown.
